Tabby Parker & Miriam M. Smith
Letters Patent

The Schedule referred to in these Letters Patent and making part of the same containing a description in the words of the said Tabby Parker and Miriam M. Smith themselves of their improvement in the machine for shelling corn

To All to Whom These Presents Shall Come Be it known that we Tabby Parker and Miriam M. Smith of the City of Richmond and State of Virginia have invented new and useful improvements in a Machine for shelling corn and that the following is a full and exact description of the construction and operation of the said Machine as invented and improved by us. This machine consists of a frame, a cylinder, gear wheels, a hopper a spout, crank &c. The frame is two feet 5 $\frac{1}{2}$ inches long and 3 feet 4 inches wide at its feet. It consists of four posts 3 feet 6 inches long 3 inches square and of five girths formed together in the following manner. Two posts at each end of the machine are placed together in a triangle form they are halved together at the top and come to a point and fastened together by bolts and nuts. the feet spread two feet four inches & forming a complete brace. Each of these two ^{ends} posts have a cog girth three inches square tenoned through them three inches from their feet and are secured by pins. Then two end frames are connected together by three girths 2 feet 3 $\frac{1}{2}$ inches long exclusive of tenons & 3 inches square. one of which is tenoned into the left hand posts on the top side six inches from their feet and immediately above the cog girths one other is tenoned into the cog girths three inches from the right hand posts and the other one is tenoned into the right hand posts one foot four inches from their feet which girths are secured by pins or bed screws. Two feet six inches from the feet and one foot from the top in the centre of the right hand posts, is the cylinder shaft upon which the cylinder is hung which shaft is of wrought iron and is 2 feet 7 $\frac{1}{2}$ inches long and 7 $\frac{1}{2}$ or 8 inches square. It has bearings turned at each

Apr 9 1831

and 24 inches long. On the crank end of this shaft, or may be put on either end, is a spur pinion 4 inches in diameter and one inch thick with a hub projecting half an inch, which pinion has 15 teeth and is fitted firmly upon the shaft and square with the end of the cylinder, and the hub even with the shoulder of the bearing. The cylinder is two feet long & 13 inches in diameter at each end, it is gradually diminished in the centre one eighth of an inch or sufficient to bring it when turned equal distance from end to end from the ledger in its declining position with the side of the cylinder. The cylinder is made of a solid stick of oak or other seasoned hard wood or of seasoned oak or other hard wood plank and staves 1/8 inch thick. When made of plank and staves, the heads are of two thicknesses with their grain intersected to prevent splitting and are nailed or screwed together. These heads are fitted firmly upon the shaft at their proper places and are then turned upon the shaft to such size as with the thickness of the staves will make the sized cylinder wanted. The staves are three or four inches wide, their edges are jointed beveling like barrel staves, their ends hollowed and fitted upon the heads and are placed close together and nailed or screwed firmly to the heads. The cylinder is then turned in a lathe or in its destined place to make to the size and dimensions before stated. Eight iron plates or ribs are placed spirally and at equal distance from each other upon the cylinder, extending from end to end with their thick edges to the left or towards the hopper and are made fast to the cylinder by screws and nails. These rods are half an inch wide and 2 1/2 or 3/4 of an inch thick on one edge and half that thickness on the other edge, and two inches of their foot ends are bent to the right or towards their thin edge forming a knee, the ends being turned one inch from the straight line of the rod. To find where to place these rods upon the cylinder make a dot at the crank end of the cylinder from which strike a direct line to within 1/4 inch of the other end and from thence measure back to the right upon the surface of 1/4 inches and make another dot and place the end of the plate or rod upon the first dot and the knee upon the 2^d and secure it there and the other rods are placed in the

the same direction of the first and at equal distances from each other, three and a quarter inches above the cylinder shaft are seen the upper or outer edge of the right hand posts is the crank shaft which is of round or square enough iron $\frac{3}{4}$ or $\frac{7}{8}$ of an inch in diameter and has a bearing turned at the foot end 11 inches long and one on the crank end three inches long; it passes through the post and has a crank upon the end; it is secured to the posts by caps and screws, one half of the diameter of the shaft being let into the posts and the other half into the caps. Upon this shaft immediately over the pinion on the cylinder shaft is a spur wheel 12 inches in diameter and one inch thick in iron and $\frac{1}{2}$ inch at hub. It has 45 cogs which gear into the pinion by which, and the crank on the end of this shaft the machine is put in operation, and which gives the cylinder three evolutions to one of the crank. Upon the outside of the left hand posts at the side of the cylinder is a ledge, the bottom of which runs parallel with the cylinder and the top is square and plated with iron and forms the bottom of the hopper. This ledge is two inches thick and 6 inches wide at the crank end and 3 inches wide at the other end, making a descent from one end to the other of 3 inches. It is let into the posts 1 foot $1\frac{1}{4}$ inches from their feet so as to stand erect on edge and the top within $\frac{3}{5}$ of an inch of the ribs upon the cylinder, and the crank end half an inch above, and the other end two and a half inches below the center of the cylinder and is then made fast to the posts by screws or nails. The foot end of the ledge below the end of the cylinder is shaped, and with the posts is hollowed out so as to give free passage to the oats. Immediately above the ledge and running parallel with it is a board of nearly the same length of the hopper, the upper end being concave and its foot extending the length of the cylinder. This board is six inches wide and one inch thick and stands nearly erect on edge a little leaning to the cylinder and two inches of the inside bottom of it is plated with iron and with the ledge forms the hopper. It is elevated upon two perpendicular wood springs, just high enough for its bottom to clear the top of the ledge. The springs are placed upon

fifteen inches apart, the upper one is ground joints and the other one is nailed or secured to the outside back of the hopper. The springs are five feet long & inches wide and half an inch thick and pass through a revolving girth placed in their centre and have a thin ledger nailed to their back which rests upon the revolving stay girth supporting the hopper at its proper height and the feet of the springs enter two Mortises in a slide girth which rests upon the two end girths. The revolving stay girth is 3 inches square and is tenoned into the centre of the left hand posts 1 foot 6 inches from their feet by round tenons on which it turns to accommodate the movement and spring of the hopper. The slide girth is 1/2 inch wide and 1 inch thick and has a bolt at each end which passes through elong mortises in the end girths and through said slide girth with nuts upon the top by which it is secured to the end girths wherever wanted, and by sliding this girth which governs the feet of the hopper springs the hopper swings upon the revolving stay girth and is enlarged or diminished to suit any sized ears and is then secured by said bolts and nuts. The spout which conveys off the corn as shelled is made of boards half an inch thick, it is 1 foot 8 inches long and 2 feet 2 inches wide. The upper end of the bottom of the spout is nailed to the bottom of the ledger and the lower end rests upon and is nailed to the right hand girth; its sides are six inches high and are nailed to the bottom. The upper end fitting to the ledger. The operator turns the crank with his right hand and puts the ears into the hopper with his left, and the springs of the hopper bear them to the cylinder while the iron ribs upon it strike them, turn them swiftly round, shell them, and force the ears out at the foot of the hopper, with great rapidity and the corn is conveyed off by the spout to itself. The great improvements made in this machine for which we claim an exclusive right as original inventors, consists 1st in gearing it and applying a crank to an extra good shaft immediately over the cylinder by which the speed of the cylinder is increased three fold and may be increased its movement concealed so as to fit into the hopper upon the

the opposite side of the cylinder from what has heretofore been done and convenient to the operators left hand, thereby enabling him to turn the machine with his right hand and feed with his left which saves the labor of a second person to feed as heretofore required. 2° in applying the centering girth as a stay to the center of the hopper springs, and a side girth, bolts and nuts to the feet of said springs by which they have double the length of spring and the hoppers is varied to suit any sized ears of corn with much more ease and in one quarter of the time required to do it by means of the cylinder by means of wedges as heretofore done. 3° in bending the ends of the iron ribs placed upon the cylinder by which means the ribs are forcibly thrown clear from the machine. and 4° in making the frame, in an easy simple triangle form, thereby making it a firm substantial brace to itself. By those improvements the machine is made for about the same expense of the former kind and is more substantial and durable and less liable to get out of order and is easier managed, will do the work better, and about three times as fast & with only half the labor. =

In witness that the foregoing is a true specification of said corn-shelling machine as improved by us we have hereunto set our hands and seals this 15th day of February 1831
